UNITED STATES PATENT OFFICE.

WILLIAM J. GRIEBEL, OF FORT WAYNE, INDIANA.

FOLDING BEDSTEAD.

SPECIFICATION forming part of Letters Patent No. 397,183, dated February 5, 1889.

Application filed February 3, 1888. Serial No. 262,904. (No model.)

To all whom it may concern:

Be it known that I, WILLIAM J. GRIEBEL, a citizen of the United States, residing at Fort Wayne, in the county of Allen and State of Indiana, have invented certain new and useful Improvements in Folding Bedsteads; and I do declare the following to be a full, clear, and exact description of the invention, such as will enable others skilled in the art to which 10 it appertains to make and use the same.

This invention relates to improvements in that class of beds known as "folding" beds; and it has for its object, together with neatness of finish, simplicity of construction and 15 ease of operation.

The invention will be fully understood from the following description and claims, when taken in connection with the accompanying drawings, in which—

20 Figure 1 is a longitudinal section showing the bed extended in a position for use. Fig. 2 is an interior view, partly in section, of the lower portion of the stationary frame. Fig. 3 is an end view. Fig. 4 is a detail elevation 25 of the pivoted or bed section, and Fig. 5 is a perspective view of one of the dovetail bars for retaining the journals of the bed-frame in spurred rocker-bearings. Fig. 6 is a detail view showing the dovetails in the offset.

30 Referring by letter to the said drawings, A indicates a stationary upright frame, which is designed to receive and support the bed-frame B. The lateral walls of this frame A are set forwardly a sufficient distance at their base, as 35 shown at a, and on the inner sides of the offset walls are provided fixed horizontal bearings b, which bearings are provided with a suitable number of apertures, c, which are designed to receive short legs or prongs of the 40 rocker-bearings D, as will be presently explained.

The rocker-bearings D have their bearings on the horizontal fixed bars b of the offset walls a, so that they may be allowed to rock in a 45 plane relatively at right angles to the stationary frame A, and these rockers are guided in their movements by means of guard-bars e. These rocker-bearings taper upwardly, as shown, so as to permit the same to move within 50 a given space, and terminate in open eyes f, which are designed to receive the journals E, arranged in the outer sides near the inner

ends of the side rails of the bed-section B. This bed-section B may be of any suitable size and design, according to the dictation of 55 the mechanic, so as to conveniently fold up into the stationary frame A. The front vertical rail g of this offset a and also the front vertical rail h of the stationary section A are provided with corresponding dovetail 60 grooves, i, which have an inner stop, l. These grooves and stops are on a line with the top edge of the offset walls a, and are designed to receive the dovetailed ends F, which, when 65 in position, serve as a means of preventing the journals of the bed-frame from being lifted out of the open eyes in the rocker-bearings.

Secured to the inner lower sides of the side walls, G, of the stationary frame are two curved parallel strips or castings, H, the upper ends of which are carried to a point slightly above the opening I, caused by the guard-bar e on the offset walls and the face-edge strip h of the stationary frame. These curved guides H are shown as of a compound 70 curvature in outline, and are designed to receive between them rollers L, which are journaled on the outside of the side rails of the bed-frame above and in advance of the fixed journals E. On the rear side of the head-board of the bed-frame is provided a box or receptacle, M, into which suitable weights 75 may be placed to assist in swinging the bed-frame on its pivots.

From the construction illustrated it will be 80 seen that to connect the bed-frame with the stationary frame the bars F must first be removed from the upper edges of the offset walls a and the rocker-bearings placed in position, as shown in Fig. 2. The bed-frame is 85 then lifted over the said offset walls and its rollers L brought to bear on the bars e, which 90 will serve as tracks therefor, when the said frame is pushed in until it passes through the interspace I. It is then lifted again so as 95 to bring the said rollers between the curved guide H, when it is let down and the journals E let into the open eyes f of the rocker-bearings D. The bars F are then replaced, as shown in Fig. 2, when the said bed-frame 100 will be prevented from leaving the bearings and the parts all held in proper working position.

By reference to Fig. 2 of the drawings it

will be seen that the forward guide-strips, H, have an offset or recess, P, at their upper ends, which are designed to receive the rollers L when the bed-frame has been let down 5 in a horizontal position. At this operation the rocker-bearing will assume the position shown in dotted lines. The rear guide-strips have their upper end extended slightly above these recesses or offsets in the forward strip 10 and their inner sides are curved as shown, so that when the bed has been lifted in the act of folding or closing its rollers will be properly guided down the curved way formed by the said strips. I attach importance to 15 these features of construction, as it will be seen that when the bed has been let down so as to bring the rollers into the recesses or offsets in the guide-strips it will be effectually locked or prevented from accidentally lifting, 20 as sufficient force must be first applied to the bed-frame to lift its rollers out of the recesses of the strips before the said frame will be permitted to close. It will not, however, require great force to lift the bed, as by the employment of the rockers, when they start to move 25 rearwardly on their bearings, the rollers will be lifted from the said recesses.

The space shown in the upright stationary frame back of the head-board may be closed by 30 strips of board or webbing, the latter being preferred, so as to prevent the pillows from falling out or rubbing against the wall when the bed has been closed.

I am aware that it is not new to provide an 35 upright frame with an offset having a serrated bearing or a bearing with notches, and arranged upon this bearing a toothed vibrating lever which supports one end of a movable frame.

I am also aware that it is not new to provide a fixed frame with curved guideways in which 40 rollers of a pivoted frame move, and therefore do not claim such devices, broadly.

Having described my invention, what I claim is—

1. The combination, with the main frame 45 having the offset, as described, and provided with the dovetailed grooves in the tops of the side walls, of the movable bars F, having their ends tenoned to enter the said groove, the rocking bearings notched at their upper ends 50 to receive journals of the bed-frame, having the rollers L on the upper outer sides of the side rails, and the vertically-curved guides H, arranged in the stationary frame and having the offsets P at their upper ends, substan- 55 tially as specified.

2. In a folding bed, the combination, with the main frame having the offset, as described, 60 o' the horizontal bearings b, provided with apertures c, the guard-bar e, the rocking bear- 65 ings D, having the bearing-notch at their upper ends and prongs at their lower ends to enter the apertures of the fixed bearing b, the vertically-curved guides H, secured to the side walls of the stationary frame and having the 70 offsets P at their upper ends, and the bed- section B, having the lateral studs E, to enter the notches of the rocking bearings, and the rollers L, to enter the curved guideways H of the main frame, substantially as specified.

In testimony whereof I affix my signature in presence of two witnesses.

WILLIAM J. GRIEBEL.
